(57) **CLAIM**

The ornamental design for a display and key array for a communicator, as shown.

DESCRIPTION

FIG. 1 is a left side view of the display and key array;

FIG. 2 is a front view thereof;

FIG. 3 is a right side view thereof;

FIG. 4 is a bottom plan view thereof;

FIG. 5 is a perspective rear view thereof in open position; and,

FIG. 6 is a perspective front view thereof.

The broken line showings of a communicator throughout the views are for illustrative purposes only and form no part of the claimed design.
